UNITED STATES PATENT OFFICE.

JOHN J. LÜCK, OF RIPON, WISCONSIN.

BARREL.

SPECIFICATION forming part of Letters Patent No. 242,948, dated June 14, 1881.

Application filed April 19, 1881. (No model.)

To all whom it may concern:

Be it known that I, JOHN J. LÜCK, a citizen of the United States, residing at Ripon, in the county of Fond du Lac and State of Wisconsin, have invented new and useful Improvements in Barrels, of which the following is a specification.

This invention relates to that class of barrels in which the barrel is composed of a flexible sheet or series of staves that can be either rolled into compact form or unrolled and securely held and locked in barrel shape.

The improvement consists in certain means for locking the meeting edges of the said flexible sheet or series of staves, and for securely binding the staves together, as hereinafter described and claimed.

In the drawings, Figure 1 is a side elevation of the complete barrel. Fig. 2 represents two sections of the flexible sheet or series of staves which constitutes the barrel, and shows the inner sides of the meeting edges of the same, in order to illustrate the locking devices. Fig. 3 is a perspective view of one of the locking plates. Fig. 4 represents one of the keys. Fig. 5 represents a portion of two of the meeting edges of the flexible sheet of staves locked together. Fig. 6 is a top or plan view of Fig. 1, and illustrates one end of the barrel. Fig. 7 illustrates a wooden hoop with the locking devices secured thereto. Fig. 8 is a form of fastening devices secured upon a metal band, said fastening being in some instances employed in addition to the fastenings G H, as hereinafter described. Fig. 9 represents a flexible sheet or series of staves unfolded. Fig. 10 is a section taken on the line *xx*, Fig. 5.

The barrel herein represented is composed of the requisite number of staves A, flexibly connected together by means of the wires B. These wires lie in the grooves C, that are formed in the inner faces of the staves, and transversely to their length. The wires also pass through staples D, that are secured to the staves over the grooves therein, one or more staples being secured over each groove. The above constitutes a flexible sheet or series of staves held closely together, which sheet can be rolled to occupy much less space than the barrel, or the edges of the same can be brought together to form the full-sized barrel.

In order to hold the meeting edges of the sheet together so as to form the barrel I provide locking devices constructed and arranged as follows:

55

E indicates the hoops, one of which will be at each end of the barrel, and two or more arranged intermediate of the said end hoops. One end of each hoop is secured by rivets *e e* to the stave at one of the meeting edges of the 60 flexible sheet of staves, while the remaining ends of the hoops or straps pass freely through staples F, that are secured to a stave at the opposite edge of the said sheet. These free ends of the hoops, which extend beyond the 65 staples, are provided with hooks G, the hook-shaped portion of which is upon the inner side of the strap.

A locking-plate, H, is provided for the reception of each hook, said locking-plates being 70 securely riveted to the inner face of the stave *h*, to which the secured ends of the straps are fastened upon its outer side. The rivets *e e*, that pass through the hoops and stave, also pass through the locking-plates, whereby the 75 parts will be firmly held together. The locking-plate provided for the hook consists of a bed, *h'*, and two parallel side flanges, *II*, with curved and channeled top edges, *h''*, between which flanges the hook passes when the meeting edges of the flexible sheet of staves are brought together to form the barrel. The outer end of the bed portion of the locking-plate is beveled, as illustrated in Fig. 10, and that portion of the outer edge of the stave *i* which 80 will be under the hook end of the hook is beveled down to the plates K, so that the opposing edges of the flexible sheet of staves can be brought squarely and closely together, with the hook upon the inside of the barrel, the said 85 beveled portions affording room for the ends of the hoops or straps to which the hooks are secured, as will be seen by referring to Fig. 10, and more clearly understood when taken in connection with the description of the manner 90 in which the two parts of the locking devices are brought together and interlocked. At the outer edge of each flange is a projection, *I'*, that is beveled upon its under side, and upon the inner face of the stave *i* is a plate, K, upon 95 which the beveled edges of the projections of the flanges bear when the sheet of staves is

- brought into barrel form. Each of these flanges of the locking-plates is also provided with a notch, L, the purpose of which will be explained in connection with the locking-keys M. 5 The conformation of such key is that of a wedge provided with a lip, m, at the butt-end thereof, to enable the operator to engage therewith a claw-hammer or other suitable tool, in order to withdraw the same when the key is held by the 10 locking devices. The key can have a hole, through which a screw can be passed for preventing it from slipping; or a plate or piece can be secured to the barrel over the head of the key. The inner faces of the staves are 15 grooved, as at N, to receive the edge of the heads. The heads will be provided with notches P P', so that they will fit closely upon the locking devices and the wedges, and also to permit the wedges or keys at the heads of the 20 barrel to pass through, the notch P being more especially provided for the hook and key and the notch P' for the plate K. In forming the barrel the flexible sheet is brought into cylindrical form and the hooks passed between the 25 flanges of the locking-plates until the notch of the hook passes the notches of said flanges, after which the keys are inserted between the notches L L of the flanges and the hook. The wedges or keys are then driven and wedged 30 between the same until the meeting edges of the two wide staves are held firmly together and the hoops drawn tightly upon the barrel. 35 It will be remembered that the hoops are secured at one end and left free at the remaining ends that pass through the staples, and hence they can be drawn tightly upon the barrel. This operation also serves to secure the heads in place, one of which will be sprung in after the central locking devices have been 40 secured by the keys. 45 The grooves h³, before referred to, in the flanges I of the locking-plates, are made so that should the plate be set to bring either flange in line with the groove N in the staves in which the head fits the head can be beveled and adapted to fit into said groove in the flange in the same way that it fits into the groove N. 50 As shown in Fig. 9, the wires lie in grooves in the staves. Each will be fastened at one 55 end of the flexible sheet of staves, and, passing through staples D on all of the staves, finally passes through a staple, R, upon the last stave, after which it will be formed in a knot to prevent slipping. These staples can be passed through washers r, which can be arranged upon each side of the stave, if desired. 60 Fig. 7 shows a wooden hoop with a locking-plate. In this case the plate H and shank or plate of hook G are riveted to the hoop, or 65 they can be secured thereto by staples S, as shown. The locking-plate and hook, in this case, should be the same, or substantially the same, in construction as those already described in connection with the previous figures. 70 65 In Fig. 8 the catch is formed of a metal strap, and is adapted to engage a broad metal loop, V, upon the opposite end of the hoop. This form of fastening is only intended to be used, when preferred, in place of the two hereinbefore-described inner locking devices that 75 are between those at the ends of the barrel, said end fastenings being, however, constructed in accordance with my invention, as already described, and secured together by means of the keys. 75
- If desired, the locking devices can be arranged outside of the barrel-heads, the keys locking the same passing through openings at the edges of the heads, and in place of the locking devices near the center of the barrel, 80 as shown in Fig. 2, the locking device shown in Fig. 8 can be employed, as already stated. 85
- If preferred, rivets at the free ends of hoops E can be arranged on the under side of the hoops and fit in slotted plates secured to the barrel.
- From the above it will be seen that the edges of the flexible sheet of staves can be brought squarely together and held by the locking devices, which latter will be concealed 90 within the barrel, excepting at the ends thereof. But in all instances the locking devices will be upon the inner faces of the staves when the flexible sheet of staves is brought into barrel form and secured, as set forth, whereby 95 the outer surface of the barrel between its ends will be smooth, and no projections will occur to injure the hands of persons lifting the barrel or to interfere with the rolling of the same. Moreover, the locking devices will 100 be protected from injury.
- What I claim is—
1. The combination, with the barrel comprising a close flexible sheet consisting of staves held together by means which permit 105 their moving toward each other, of the hoops secured at one end and provided at their free ends with hooks, and devices adapted to engage said hooks, arranged upon the inner side of the barrel at one of the meeting edges of 110 the sheet of staves, the said sheet or series of flexibly-connected staves being bent into barrel shape, and the free ends of the straps being passed between the meeting edges of the sheet and the hooks connected with the interior locking devices, whereby the said locking devices are all upon the inner sides of the staves, substantially as described. 115
  2. The combination, with the barrel comprising a close flexible sheet consisting of 120 staves held together by means which permit their moving toward each other, of the hoops secured at one end and provided at their free ends with hooks, the locking-plates provided with notched side flanges, and the wedge-shaped keys adapted to be wedged in between the hooks and the notched portions of the flanges, substantially as described. 125
  3. The combination, with the barrel comprising a flexible sheet consisting of staves 130 held together by wires lying in channels and passing through staples upon the inner faces

of the staves, of the locking devices adapted to hold the meeting edges of the staves at the meeting edges of the sheet of staves together, hoops arranged to be drawn tight upon the barrel by means of the locking devices, and the barrel-heads held in grooves, substantially as described.

4. The combination, with the barrel comprising a series of staves flexibly connected together, of the surrounding hoops E, secured at one end, and provided at their free end with hooks G, the locking-plates H, provided with notched flanges having the projections I', the wedge-shaped keys, and the plates K,

upon which said projections bear when the flexible sheet of staves is brought into barrel shape and the hoops drawn tight by wedging the keys between the hoops and the notched portions of the flanges of the locking plates, substantially as described.

In testimony whereof I have hereunto set my hand in the presence of two subscribing witnesses.

JOHN J. LÜCK.
